UNITED STATES PATENT OFFICE

105,544

DESIGN FOR A SHOE

Jerome Edson Andrews, Andover, Mass.

Application June 14, 1937, Serial No. 69,836

Term of patent 3½ years

To all whom it may concern:

Be it known that I, Jerome Edson Andrews, a citizen of the United States, residing at Andover, in the county of Essex and Commonwealth of Massachusetts, have invented a new, original, and ornamental Design for a Shoe, of which the following is a specification, reference being had to the accompanying drawing, forming a part thereof, in which

Fig. 1 is a plan view of a shoe showing my new design, and

Fig. 2 is a side elevational view of the shoe, the outline of the same being shown conventionally in dot and dash lines.

The dominant feature of my invention resides in the tongue shown in full lines.

I claim:

The ornamental design for a shoe substantially as shown and described.

J. EDSON ANDREWS.
